UNITED STATES PATENT OFFICE.

FRED B. CHAPPELL, OF GLENS FALLS, NEW YORK, ASSIGNOR OF ONE-HALF TO GLENS FALLS MACHINE WORKS, OF GLENS FALLS, NEW YORK.

FEEDING DEVICE FOR SULFUR-BURNERS.

1,370,627.

Specification of Letters Patent. Patented Mar. 8, 1921,

Application filed April 20, 1920. Serial No. 375,393.

To all whom it may concern:

Be it known that I, FRED B. CHAPPELL, a citizen of the United States of America, and resident of the city of Glens Falls, in 5 the State of New York and United States of America, have invented certain new and useful Improvements in Feeding Devices for Sulfur-Burners, of which the following is a full, clear, and exact description.

10 This invention relates to improvements in feeding devices for sulfur burners, and the object of the invention is to provide a feeding device which will not become clogged with sulfur and which will offer little, if 15 any, resistance to the passage of the sulfur, thereby reducing the amount of power formerly necessary for feeding.

The invention resides in the formation of the spout through which the sulfur is fed 20 into the burner. The practice has previously been to provide a spout projecting a considerable distance into the burner and closed at the top and at the upper portion of the discharge end. The purpose of the 25 mechanical feed is to supply sulfur in its raw state to the burner and to supply this sulfur without its being melted at all in the spout is desirable. The temperature around the spout is very considerable, and with a 30 view to preventing sulfur melting in the spout, the spout was formed as previously described to protect the sulfur as much as possible. What really happened was, that the sulfur acquired enough heat from the 35 spout to become sticky and resist movement through the spout, with the result that a dam of sulfur formed at or near the outlet. The closed top and restricted outlet caused the sulfur in this dam to become packed 40 and the resistance to feeding necessitated the use of considerable power. After the sulfur dam remains a sufficient time in the mouth of the spout, the lower portion thereof in contact with the hot spout melts and 45 the dam goes out with a rush. The result is that the sulfur is fed intermittently and in comparatively large quantities into the burner instead of in a uniform continuous manner.

50 According to this invention, the spout is made much shorter than heretofore and projects only a sufficient distance into the burner to properly deliver the sulfur thereinto. The upper part of the spout is cut 55 away for the greater part of its length and

the end opening left entirely without restriction. It has been found that, although the sulfur passing through the spout is exposed to heat, it does not melt and that the absence of any restriction of the outlet enables the sulfur to leave the spout more rapidly so that it does not block the spout.

In the drawings which illustrate the invention:—

Figure 1 is a fragmentary end elevation 65 of a sulfur burner and feeding device partly in section.

Fig. 2 is a perspective view of the spout alone.

Referring more particularly to the drawings, 11 designates the revolving drum of a sulfur burner having a frusto-conical end 12 into which the feeding device projects. The feeding device comprises a hollow body 13 carrying a supply hopper 14 and a feed 70 screw 15. A spout 16 is provided at the discharge end of the body 13 and projects a short distance into the burner but not beyond the frusto-conical end 12. The spout comprises a cylindrical body 17 having at 75 one end a finished portion 18 which fits accurately within the body 13. Approximately two-thirds of the length of the projecting portion of the spout is cut away above the horizontal diameter, as indicated 80 at 19, so that the discharge end of the spout is an open trough. This spout is considerably shorter than the spouts heretofore used so that it projects only a comparatively 85 short distance into the burner. The open 90 discharge end offers no resistance to the escape of sulfur so that the sulfur, which is advanced by the feed screw, does not linger in the spout. The fact that the spout is open and exposes the sulfur to the heat of 95 the burner is compensated for by the reduced length so that the sulfur melts very little, if at all, in the spout. The unrestricted opening allows any masses of partly melted sulfur to escape without blocking the 100 spout. The sulfur is fed through a spout according to this invention in a substantially continuous and uniform manner and with much less power expenditure than heretofore.

Having thus described my invention, what I claim is:—

1. A feed spout for sulfur burners open at its discharge end and at the top adjacent the discharge end.

105

110

2. A feed spout for sulfur burners adapted to be connected to the feeding device and to project a short distance into the combustion chamber of a burner, said spout being unrestrictedly open at its discharge end and for a portion of its length above the horizontal diameter.
3. A feed spout for sulfur burners comprising a tubular inlet portion and a trough discharge portion having an unrestricted discharge end.
4. A spout for sulfur burners adapted to be connected to the feeding device and to

project a short distance into the combustion chamber of a burner, said spout comprising a tubular inlet portion and a trough shaped discharge portion having an unrestricted discharge end, the arrangement being such that the portion of the spout projecting beyond the feeding device is tubular through approximately one third of its length and trough-shaped through approximately two thirds of its length. 15 20

In witness whereof, I have hereunto set my hand.

FRED B. CHAPPELL.
